(57) **CLAIM**

The ornamental design for a motor, electric, as shown and described.

DESCRIPTION

FIG. 1 is a front elevation view of a motor, electric showing the new design;

FIG. 2 is a rear elevation view thereof;

FIG. 3 is a first side elevation view thereof;

FIG. 4 is a second side elevation view thereof;

FIG. 5 is a top plan view thereof; and,

FIG. 6 is a bottom plan view thereof.

The broken lines shown depict the portions of the motor, electric that form no part of the claimed design.
